UNITED STATES PATENT OFFICE.

FRANK COWLES AND HENRY M. MORRILL, OF TEKONSHA, MICHIGAN.

ROCKING-CHAIR.

No. 892,937.

Specification of Letters Patent.

Patented July 7, 1908.

Application filed June 14, 1906. Serial No. 321,744.

To all whom it may concern:

Be it known that we, FRANK COWLES and HENRY M. MORRILL, citizens of the United States, residing at Tekonsha, in the county of Calhoun and State of Michigan, have invented certain new and useful Improvements in Rocking-Chairs; and we do hereby declare the following to be a full, clear, and exact description thereof, such as will enable others skilled in the art to which it appertains to make and use the same, reference being had to the accompanying drawings, which form a part of this specification.

Our invention relates to that class of chairs in which two oppositely-disposed seats are arranged and connected by a common framework provided with double rocking elements between which a detachable, oscillating foot board may be suspended to actuate the respective rockers, and the object of our invention is to provide a chair capable of being swung with but little exertion; whereby the motive power may be regulated as occasion may require; whereby the same may be quickly and easily dismantled and folded into very small space; whereby the foot board may be removed and used as an extension to the seat portions and make a swing couch or bed.

Other objects and advantages will appear in the following specifications and will be particularly pointed out in the claims which follow these specifications, in which

Figure 1 is a perspective view of our improved chair. Fig. 2 is a rear view of the same from the right. Fig. 3 is a side view taken on the line x, x , of Fig. 2. Fig. 4 is a detail in perspective of a rocker bracket. Fig. 5 is a longitudinal section through the rocker-gear bracket, and the frame and back side portions. Fig. 6 is a perspective view of the rocker-bracket, locking spring. Fig. 7 is a perspective view in modification. Fig. 8 is a detachable foot-board section, and Fig. 9 is a longitudinal section of Fig. 7 with the foot-board interlocked between the seat sections to form a lounge or bed.

Like marks of reference refer to corresponding parts throughout the different views.

A, represents the back, B, the seat, C, the foot board, D, the rockers, and E, the main frame sections. Each of the rocker sections comprises double rockers, D, suitably separated, and connected by a rung, 1, upwardly-inclined standards, 2, having at their bottoms a connecting brace, 3 and a top bracket,

4, to which the standards are riveted, as shown in Figs. 1 and 2.

The body or frame of the chair proper consists of the oppositely-disposed drop-frame sections, E, comprising the outwardly and upwardly diverging wings, 5, and bottom connection, 6. The section, 6, is secured to the wings by means of the bolts, 7, at either end thereof, and by secondary bolts provided with the thumb nuts, 8, a means whereby the wing sections may be folded when such may be necessary for crating or arranging for transportation.

Connecting at the upper ends of the sections, 5, the backs, A, of the respective chairs are mounted, the seats, B, being pivoted to the sections, 5, by cross rods, 9, below the pivotal connection with the back sections, the outer ends of the seats being braced by side supports, 10, having slotted bottoms, 11, which rest on pins, 12, of the aforesaid wings. That the chair backs may be adjusted to varying angles, bails, 13, are received at their upper looped ends within notches, 14, along the respective backs, their lower free ends engaging the seat braces, 10, springs, 15, of the chair backs preventing the bails from dislodgment until released by the operator.

Each of the brackets, 4, is formed with a square, longitudinal hole for receiving square connecting rods, 16, and has a cylindrical, inner end, 17, which forms a journal adapted to receive the back and body sections at their points of union, and from which points the backs are adapted to be tilted, and also folded, a rib, 18, forming a collar and preventing inner thrust of a bracket when mounted.

Depending from the outer end of a bracket, diverging arms, 19, are formed, to which the upper ends of the standards, 2, are riveted, a longitudinal, open-ended slot, 20, in the upper face thereof being fitted with a curved spring, 21, having a lip adapted to engage a recess or pocket, 22, of the square shaft, 16, to secure said bracket in position, as shown in Fig. 5.

From the outer extremities of the seats, B, and suspended from cross ties, 23, the hooked ends of bails, 24, are supported. These bails, at their looped ends, receive the extremities of a foot board, C, said board being formed with under-cut gains, 25, for receiving said bails.

Connecting with the loop of the bail to

the right, a pitman, 26, is attached to the lower end of an arm, 27, the upper end of which forms a gear segment, 28, the same having a stud, 29, operative from a bracket, 30, secured to the under side of the frame section, 5. The bracket, 4, of the chair to the right, forms a secondary gear segment, 31, meshing with the lever segment, 28, as aforesaid. As motion is imparted to the foot platform, C, the pitman, 26, will swing the lever having the segment, 28, and communicate motion to the bracket segment, 31, thereby causing the chairs to oscillate in unison.

15 Preparatory to crating or laying aside for the season, the brace sections, 10, are raised to clear the pins, 12, and the seats, B, folded between the wings, 5, the brackets, 4 pulled from the cross bars, 16, the bars removed, 20 whereby the backs, A, will be separated from the wing sections, and the bails, 13, released from the notches, 16, whereby the bails will lie in parallel arrangement with the wing sections, or nearly so. The thumb-nuts, 8, will also be removed and the sections, 5, together with the seat, B, braces, 10, and bails, 13, fold and lie together, and the standards, 2, of the rocker sections may thence be made to stride the already folded sections 30 and complete the folding of the chair, all of which may be done easily and speedily, without the aid of tools.

In the modification shown in Figs. 7 and 9, the seat sections, B, are pivoted to the lower extremities of the chair backs, A, by a cross rod, 9', and the side braces, 13' are adjustable with the seat braces 10' through the medium of the holes within the seat braces, as shown. The rockers, D, have 40 standards, 2', which unite at their tops and form trunnions, 4', for receiving the side sections, 5, of the frame. To one set of the standards to each set of rockers the standards are provided with cranks or handles, 45 F, by which motion may be imparted to the rockers. The foot platform, C, may be detached from the cross bars, 8', and fitted between the seat sections, B, by seating the gains, 25, thereof, over the cross braces, 23, 50 and afford a lounge or bed. In Fig. 3 the section, C, may be removed from the bails, 24, in like manner and fitted between the seat sections on the cross braces, 23.

What, therefore, we claim as new and desire to secure by Letters Patent, is:—

1. In a rocking chair, the combination with rocking elements, a framework connecting said elements, backs pivotally supported from said framework, seats pivotally supported below said backs to said framework, brace elements suspended from said seats to said framework, bails suspended from said seats, a foot platform connecting said bails, and a pitman connecting said foot platform 60 to one of said rocking elements.

2. In a rocking chair, the combination with rocking elements, of a collapsible framework connecting said elements, chair backs pivotally supported at either end of said framework at the pivotal connection with 75 said rocking elements, said chair backs having notches in the rear thereof, chair seats pivotally supported to said framework below said chair backs, brace elements having slotted lower extremities adapted to be seated on pins in said frame work and pivotally connected at their upper ends with said chair seats, bails pivoted at their free ends to said brace elements, their looped ends engaging the notches of said chair backs, and springs 80 secured to said chair backs to retain said bails, as, and for the purpose set forth.

3. In a rocking chair, the combination with rocking elements, a framework pivotally connecting said elements, chairs supported at either end of said framework, of bails suspended from said chairs, a foot platform detachably mounted upon said bails, a primary gear segment fastened to one of said rocking elements at its pivotal connection 85 with said framework, a secondary gear segment meshing with said primary gear segment and pivotally suspended from said framework, and a pitman connecting said foot platform with said secondary gear, as 90 and for the purpose set forth.

4. In a rocking chair, the combination with rocking elements, a framework pivotally connecting said elements, chairs supported at either end of said framework, of bails suspended from the seats of said chairs, a foot platform detachably mounted upon said bails, a primary gear segment fastened to one of said rocking elements at its pivotal connection 100 with said framework, a secondary gear segment meshing with said primary gear segment and pivotally suspended from said framework, a lever depending from said secondary gear segment, and a pitman connecting said foot platform with said lever, as, and for the purpose set forth.

5. In a rocking chair comprising adjacently-fronting pivotal rocker elements, a framework connecting said elements, of brackets secured to standards of the rocker elements at the pivotal connection with said framework, said brackets being provided with oppositely-disposed square holes, notches intersecting said holes, springs fitted within said notches, cross-rod having notches near either end thereof and adapted to fit within and connect said brackets on oppositely-disposed rocker elements, said springs adapted 115 to engage the notches of said cross-rods and removably secure said elements at their pivotal connection with said framework, as and for the purpose set forth.

6. In a rocking chair comprising adja- 130

cently-fronting pivotal rocker elements, a framework connecting said elements, of 20
framework connecting said elements, of brackets provided with a cylindrical portion 5
forming trunnions secured to the standards
of said rocker elements to form pivotal connections with said framework, said brackets being provided with a shoulder, 18, and a cylindrical portion, 17, adapted to receive said framework to form a pivotal connection 25
therewith, said brackets having the mortises, 20, fitted with the springs, 21, cross-
rods, 16, connecting said brackets and provided with gains, 22, adapted to receive the free ends of the springs, 21, when in engagement with the said brackets and removably 30
secure said elements at the pivotal connection, as and for the purpose set forth.

10 15
10. In a rocking chair comprising adjacently-fronting pivotal rocker elements, a
15 elements at their pivotal connection with said framework, as and for the purpose set forth.

7. In a rocking chair comprising adjacently-fronting pivotal rocker elements, a

framework connecting said elements, of 20
framework connecting said elements, of brackets provided with a cylindrical portion 5
forming trunnions secured to the standards
of said rocker elements to form pivotal connections with said framework, said brackets being provided with a shoulder, 18, and a cylindrical portion, 17, adapted to receive said framework to form a pivotal connection 25
therewith, said brackets having the mortises, 20, fitted with the springs, 21, cross-
rods, 16, connecting said brackets and provided with gains, 22, adapted to receive the free ends of the springs, 21, when in engagement with the said brackets and removably 30
secure said elements at the pivotal connection, as and for the purpose set forth.

FRANK COWLES.
HENRY M. MORRILL.
